Primary Examiner—Cathron Brooks

(57) CLAIM

We claim the ornamental design for a display case with cards and kiosk, as shown and described.

DESCRIPTION

FIG. 1 is a front perspective of the color display system; FIG. 2 is a right side plan view of the color display system; FIG. 3 is a front plan view of the color display system; and, FIG. 4 is a left side plan view of the color display system. The broken lines are for illustrative purposes only and form no part of the claimed design.
